Victor J. Evans ATTORNEY.

UNITED STATES PATENT OFFICE.

HARRY R. WILMOT, OF BOSTON, MASSACHUSETTS.

BANJO ATTACHMENT.

1,355,723.

Specification of Letters Patent. Patented Oct. 12, 1920.

Application filed February 10, 1920. Serial No. 357,573.

To all whom it may concern:

Be it known that I, HARRY R. WILMOT, a citizen of the United States, residing at Boston, in the county of Suffolk and State of Massachusetts, have invented new and useful Improvements in Banjo Attachments, of which the following is a specification.

The object of my present invention is the provision of a resonator attachment for 10 banjos and similar musical instruments, the said attachment being adapted to afford a blended tone of the same quality as a banjo, but of increased volume, and being so arranged to the annular portion of the banjo 15 head that an annular space is provided for the passage of the tone after the tone has entered and left the resonator. Moreover because of the said annular passage for the emission of the amplified volume of tone, the 20 use of the resonator attachment does not change the direction in which the tone passes from the banjo head.

Another object of the invention is the provision of a banjo attachment having legs 25 whereby there is no danger of the highly polished surface of the metallic portion of the resonator being marred when the banjo is laid on a table or other support.

Other objects and practical advantages of 30 the invention will be appreciated from the following description and claims when the same are read in connection with the drawings, accompanying and forming part of this specification, in which:

35 Figure 1 is a view showing my novel attachment as properly applied to a banjo head.

Fig. 2 is a plan view of the inner side of the attachment.

40 Fig. 3 is a diametrical section taken through the attachment and showing the hollow resonator formed by an inner disk of wood and an outer section of metal; the metallic section being concavo-convex in 45 cross-section in order to afford a space into which and out of which the tone given off by the playing of the banjo may pass precedent to the passage of such tones through the annular space between the perimeter of 50 the resonator and the annular banjo head.

Fig. 4 is a detail view illustrating one mode of attaching the attachment to the continuation of the neck that is usually present in a banjo head.

55 Similar numerals of reference designate

corresponding parts in all of the views of the drawings.

The banjo head 1 may be and preferably is of the ordinary well known construction, and my novel attachment may be connected 60 with the neck continuation 2 of the banjo, in the manner shown in Fig. 4, or in any other approved manner; the essence of my invention having nothing to do with the said mode of attachment specifically con- 65 sidered.

My novel resonator attachment is made up of a flat, circular diaphragm or disk 3 of thin wood, in which are apertures 4, and a thin metallic section 5 that is concavo-convex in cross-section, in order to afford 70 a tone chamber 6 between it and the diaphragm 3. The said metallic section 5 is provided with a marginal flange 7 to receive the edge of the diaphragm 3, and is 75 attached fixedly to said diaphragm by screws 8 or other means. I prefer, however, to employ the screws 8 since when used in pairs, they serve the additional function of fixedly attaching to the resonator the legs 9 80 which are disposed at right angles to the diaphragm 3 and extend outwardly from the marginal flange 7 of the metallic section 5. Carried by the legs 9 and extending laterally outward therefrom are pins 10 on 85 which are rubber coverings 11. These latter are adapted to rest as shown in Fig. 1, against the edge of the annular portion of the banjo head.

Manifestly when the banjo is laid flatwise 90 on a table or other support, the legs 9 will prevent contact and marring of the convex surface of the section 5 which is ordinarily highly polished, with a view to enhancing the finished appearance of the banjo equipped 95 with the attachment.

In the practical use of my attachment, the tones afforded by the playing of the banjo enter the resonator through the apertures 4 in the diaphragm 3 and leave the resonator 100 by the same means. By virtue of this, the volume of tone is materially amplified, and at the same time the tone is of blended quality similar to the natural tone of the banjo, this blended tone being due to the fact that 105 the resonator is partly of wood and partly of metal, which is broadly new so far as I am aware. After passing into and out of the resonator, the tone is emitted from the banjo head through the annular passage 12 110

between the perimeter of the resonator and the annular portion of the banjo head.

Having described my invention, what I claim and desire to secure by Letters-Patent, is:

1. The combination with the head of a banjo, of a resonator attached thereto and arranged relatively to the annular portion of the banjo head to afford an annular 10 sound-emitting passage between the perimeter of the resonator and said annular head portion; the said resonator comprising an inner wooden diaphragm that is apertured and an outer metallic section that is marginally attached to the inner diaphragm and is concavo-convex in cross-section with the concave side toward the wooden diaphragm to afford a chamber between it and said diaphragm.
2. The combination with the head of a banjo, of a resonator attached thereto and relatively arranged to afford a passage between its perimeter and the annular portion of the banjo head; the said resonator 20 being made up of an inner apertured por-

tion of wood, and an outer metallic section between which and the wooden portion a tone chamber is formed.

3. The combination with the head of a banjo, of a resonator attached thereto and 30 having an inner apertured portion of wood and an outer metallic portion the exterior of which is convex and also having outwardly extending legs and cushioning pins extending radially from said legs and adapted to 35 bear against the edge of the banjo head.

4. A banjo head made up of an inner apertured diaphragm of wood and an outer metallic section secured to the diaphragm between which a tone chamber is formed. 40

5. A banjo head made up of an inner apertured diaphragm of wood and an outer metallic section secured to the diaphragm between which a tone chamber is formed, 45 said metallic section having outwardly extending legs and cushioned pins extending radially from said legs.

In testimony whereof I affix my signature.

HARRY R. WILMOT.
